WALTER HERBERT TAYLOR, OF GUELPH, ONTARIO, CANADA.

SURGICAL WOUND-DAM.

1,379,660.

Specification of Letters Patent. Patented May 31, 1921.

Application filed July 8, 1920. Serial No. 394,830.

To all whom it may concern:

Be it known that I, WALTER HERBERT TAYLOR, of the city of Guelph, in the county of Wellington, Province of Ontario, Canada, have invented certain new and useful Improvements in Surgical Wound-Dams, of which the following is a specification.

This invention relates to wound dams of the same general type as that disclosed in my co-pending application No. 307248 filed June 27th, 1919, and my object is to devise a wound dam in which the pressure of the fluid used in the dam is utilized to a greater extent than in the dam disclosed in the application aforesaid to maintain fluid-tight contact between the device and the skin of the patient, thus reducing the pressure required to be applied by bandages.

I attain my object by means of the constructions hereinafter described and illustrated in the accompanying drawings in which—

Figure 1 is a vertical section of my improved wound dam with the parts in normal position;

Fig. 2 a similar view showing the parts substantially as they would appear when applied to a wound by means of suitable bandages;

Fig. 3 a plan view of the stretching device; and

Fig. 4 a plan view of a modification of the stretching device.

In the drawings like numerals of reference indicate corresponding parts in the different figures.

1 is a thin annular rubber floor, with which is connected the flexible rubber cap 2. This cap is preferably provided at its top with a stiff plate 3 of any suitable material, with which are connected the inlet pipe 4 and the outlet pipe 5. The side walls 6 of the cap may be of somewhat stouter material than the floor, and may taper in thickness from the top toward the bottom to give it the greatest pliability where pliability is needed, that is, adjacent the surface of the skin, while farther from the skin greater stiffness facilitates the application of the bandage.

With the rubber floor a rubber stretching device co-operates. This device comprises an annular member 7, the lower edge of which, when the upper part is pressed toward the rubber floor, tends to expand ra-

dially from the center and thus exert an outward stretching action on the floor by frictional contact therewith.

It is also preferable to arrange the stretching device so that an inward stretching pressure is also applied to the rubber floor. In the preferred construction the annular member 7 has an outwardly flaring annular flange 8 formed thereon at its lower edge and also an inwardly flaring annular flange 9, which flanges preferably taper from their points of connection with the annular member 7 to their lower edges. It is not essential, however, that these flanges be continuous as they may be divided as shown in Fig. 4, these divisions practically forming the flanges into a series of fingers.

I have found that the best results are obtained in applying the pressure of the bandages to the stretching member if the annular member 7 be provided with a series of upwardly projecting fingers 10. While these fingers transmit pressure as desired, they do not interfere with the equalizing of fluid pressure between the space inside the stretching member and the space between the cap and the outside of the stretching member. It is desirable that the stretching member be made as effective as possible in transmitting pressure normal to the rubber floor 1, while it should possess considerable flexibility in directions which will enable it to conform to the curved surfaces to which it is to be applied. I therefore provide the annular member 7 with a series of narrow separated wings 11 adjacent the upper edge of the ring. Under some circumstances it is desirable to roughly conform the stretching member to the contour of the part to which the device is to be applied. For this purpose I provide a ring 12 of readily bendable and non-resilient material, which is fitted into an annular flange formed around the inner side of the upper part of the annular member 7. This ring may be readily bent to any desired shape and will roughly conform the stretching device to the same shape.

I have found that it is better to form the rubber floor 1 with a thickened inner edge 13. This prevents the possibility of the flange 9 slipping over the inner edge of floor. Better sealing pressure of the floor against the surface of the skin is obtained by forming a circular flexible ridge 14 on the under

side of the floor intermediate its points of engagement with the stretching member. The elasticity of the floor holds this ridge very firmly in contact with the skin. It 5 will be seen that not only does the stretching device itself tend to hold the rubber floor in fluid-tight contact with the skin, but that as fluid readily finds its way to the upper surface of the floor, the additional 10 effect of the fluid pressure is obtained which makes leakage practically impossible.

What I claim as my invention is:—

1. In a wound dam, the combination of a thin annular rubber floor; and a rubber 15 stretching device engaging the upper surface of the floor and adapted to stretch said floor both inwardly and outwardly.
2. In a wound dam, the combination of a thin annular rubber floor; and a rubber 20 stretching device engaging the upper surface of the floor and adapted to stretch said floor outwardly.
3. In a wound dam, the combination of a thin annular rubber floor; and a rubber 25 stretching device provided with concentric annularly disposed stretching members respectively inwardly and outwardly inclined and engaging the upper surface of the floor.
4. A wound dam constructed as set forth 30 in claim 2 provided with a circular flexible ridge on the under side of the floor intermediate of its margins.
5. A wound dam constructed as set forth 35 in claim 3 provided with a circular flexible ridge on the under side of the floor inter-

mediate of its points of engagement with the stretching members.

6. A wound dam constructed as set forth 40 in claim 2 provided with a thickened inner edge for the floor.

7. A wound dam constructed as set forth 45 in claim 2 provided with a flexible rubber cap forming a water tight inclosure about the stretching device.

8. A wound dam constructed as set forth 45 in claim 2 provided with a flexible rubber cap continuous with the flexible floor and forming a water tight inclosure about the stretching device.

9. In a wound dam, the combination of a 50 thin annular rubber floor and a rubber stretching device comprising a ring, bandage pressure receiving projections at the upper part of the ring, and concentric annularly disposed stretching members at the lower 55 part of the ring respectively inwardly and outwardly inclined and engaging the upper surface of the floor.

10. A wound dam constructed as set forth 60 in claim 9 provided with a flexible rubber cap forming a water tight inclosure about the stretching device.

11. A wound dam constructed as set forth 65 in claim 9 provided with a flexible rubber cap continuous with the flexible floor and forming a water tight inclosure about the stretching device.

Signed at Guelph, Ont., this 1st day of July, 1920.

WALTER HERBERT TAYLOR.
